UNITED STATES PATENT OFFICE

LEOPOLD JURGIELEWICZ, OF PASADENA, CALIFORNIA

SAFETY-WATCH-POCKET PROTECTOR

Application filed February 14, 1931. Serial No. 515,841.

My invention relates to safety-watch-pocket protectors of the character embodied in my Patent No. 1,380,212 issued May 31, 1921.

5 It is a purpose of my present invention to provide a similar form of protector which can be attached to the inner side of a garment so as to be completely concealed, and yet correlated to a pocket so as to prevent articles 10 and particularly a watch from slipping from the pocket in the event of one stooping or bending, and to preclude the surreptitious entry of one's hand into the pocket without detection.

15 It is also a purpose of my invention to provide a protector which is characterized by its structural simplicity and easy mode of associating the fabric sheet and spring stave to completely envelop the stave and form a 20 ridge at one side of the stave which acts as an obstruction to the mouth of a pocket when associated therewith to close the mouth under the action of the stave.

I will describe only one form of safety-watch-pocket protector embodying my invention, and will then point out the novel features thereof in claims.

In the accompanying drawings:

Figure 1 is a view showing in side elevation one form of stave incorporated in the protector embodying my invention.

Figure 2 is a view showing in plan one form of fabric sheet incorporated in the protector embodying my invention.

35 Figure 3 is a view showing in plan the fabric sheet rolled to form the body or ridge of the protector, and the stave in place preceding final enclosure of the stave.

40 Figure 4 is a view showing the complete protector embodying my invention.

Figure 5 is a view showing the protector applied to the pocket of a garment.

Figure 6 is a sectional view taken on the line 6-6 of Figure 5.

45 In carrying out my invention, I provide a stave S in the form of a strip of spring metal or other resilient material which is of a length equal to or greater than the length of the mouth of the pocket with which the protector 50 is to be associated. This strip is bent upon

itself at its ends to form superimposed portions 15 which are hammered flat, and provide reinforcing portions for the ends of the strip to prevent distortion of the strip when it is flexed. Registering openings 16 are provided in the strip and end portions 15, and another opening 17 is provided in the strip medially of its ends. These openings receive threads by which the stave is secured in fixed position in the fabric covering, as will be more 60 fully described.

The fabric sheet shown in Figure 2 is made preferably of canvas, and is cut to provide a relatively wide part 18 of a length exceeding that of the stave S, and narrow part 19. I 65 have shown the narrow part as tapered in width in order to give the greatest bulk to the body which it forms when rolled on itself at its ends but this is not necessary as the fabric can be of uniform width to make a 70 body of uniform thickness.

In constructing the protector, the narrow part 19 of the fabric sheet is rolled upon itself in the direction of the wide part 18 and in such manner as to form an elongated body 75 20. This body is stitched along its length as indicated at 21 to maintain the sheet in rolled form. The stave S is now placed between the body 20 and the wide sheet part 18, in the manner illustrated in Figure 3 and secured 80 in this position by extending a thread 22 through the body 20, the opening 17 of the stave and finally through the wide sheet part 18. Thus, the stave is secured in position to permit wrapping of the sheet part 18 about 85 the body and stave so that by stitching the sheet transversely and with the threads as indicated at 23 and in such manner that the threads extend through the opening 16 of the stave, the making of the protector is completed.

It is to be noted that the wide sheet part 18 when wrapped exceeds in length that of the stave S in order to provide terminal portions 24 to permit stitching of the protector as a unit to a garment, or to use any other form of fastening means for securing the protector to the garment.

As shown in Figures 5 and 6, the protector is secured to the inner side of the garment so as to be disposed parallel to the mouth of the 100

5 pocket and with the body 20 interposed between the garment and the stave S so as to form, at the mouth of the pocket a ridge co-extensive in length with the pocket mouth and which functions to form a closure for the 10 pocket. The inherent resiliency of the stave S maintains the body 20 in closed position with respect to the pocket mouth, it being understood that the stave is secured to the garment by the fabric sheet in such manner 15 that it cannot flex without applying considerable lateral pressure thereto. Thus the body, although being on the inner side of the garment is caused to effectively function as a closure for the pocket to prevent the accidental displacement of a watch or other article from the pocket, and to preclude the surreptitious removal of articles from the pocket without detection.

20 As shown in Figures 5 and 6, the protector is secured to the lining of the garment at the back of the pocket by sewing through the fabric sheet of the protector along the line of the outside ends of the stave, the needle passing back and forth through the outside two 25 stitched corners of the pocket thus securing the protector not only to the lining but also to the two outside stitched corners of the pocket. It will be understood that the protector can be interposed between the lining 30 at the back of the garment and the cloth of the garment so as to be completely concealed even from the inner side of the garment, and in either position it effectively operates to 35 tightly close the mouth of the pocket to prevent the contents of the pocket from being shaken out or otherwise accidentally displaced.

40 It is important to note that by securing the body 20 to the stave medially of its ends as by extending threads through the opening 17 of the stave, the body cannot be displaced with the movable action of the stave when the 45 protector is fastened to a garment.

45 Although I have herein shown and described only one form of safety-watch-pocket protector embodying my invention, it is to be understood that various changes and modifications may be made therein without departing from the spirit of the invention and the spirit and scope of the appended claims.

I claim:

50 1. A device of the character described comprising a stave including a flat strip of spring metal having its end portions bent upon themselves to re-inforce the ends of the stave and eliminate sharp edges thereat and formed with openings, and a fabric sheet wrapped about the stave to form a ridge at one side thereof which is substantially co-extensive 55 in length therewith, the fabric sheet being stitched in wrapped form with certain of the stitching extending through said openings of the stave, and terminal portions of 60 the fabric sheet extending beyond the ends 65

of the stave to permit securing thereof to a garment.

2. A device of the character described comprising a fabric sheet having a narrow part and a wide part, the narrow part being rolled upon itself to form an elongated body, a spring stave interposed between said body and the wide sheet part with the latter being wrapped about the body and stave so that the two are enveloped by the wide sheet part, 70 said sheet being secured to the stave and along the body to maintain the stave in the sheet and at one side of the body.

3. A safety pocket protector comprising a spring stave having its end portions bent 75 upon themselves to re-inforce the ends of the stave and eliminate sharp edges thereat, a sheet of fabric of less length than the length of the stave rolled upon itself to form an elongated body disposed along one side of the 80 stave so that the ends of the latter project beyond the ends of the body, the sheet of fabric having another portion of greater length than the length of the stave, extending from the outer convolution of the first portion and wrapped about the latter and the 85 stave so as to completely cover the stave, the free edge of the second portion being secured to the body formed by the first portion and the ends of the second portion being 90 secured to the stave and projecting beyond the ends of the stave.
